RAZOR STROPPING DEVICE

Charles J. Lawrence, Palmyra, N. Y.

Application March 26, 1934, Serial No. 717,440

10 Claims. (Cl. 51—63)

The object of this invention is to provide a device that can be used to strop or sharpen the so-called Gillette razor blade, or any blade that is the equivalent thereof.

5 Another object of the invention is to provide a device that will strop or sharpen each side of the cutting edge alternately.

Another object of the invention is to secure this result by the movement of the strop back and forth.

10 These and other objects of the invention will be illustrated in the drawing, described in the specification, and pointed out in the claims at the end thereof.

15 In the drawing:

Figure 1 is a side elevation of my improved stropping device.

Figure 2 is a section on the line 2x—2x of Figure 1.

20 Figure 3 is a section on the line 3x—3x of Figure 1, with the strop in position to sharpen the cutting edge.

Figure 4 is a perspective view of the bridge that supports the blade that is being sharpened.

25 Figure 5 is a perspective view of the plate that is used to hold the blade on the bridge.

Figure 6 is an end elevation of the device viewed from the left of Figure 1.

30 Figure 7 shows a modified form of the stropping device adapted to be used in sharpening the blades that have only one cutting edge and are thick on the other edge, such as the so-called Gem blade.

Figure 8 is a perspective view of the bridge that 35 is adapted to be used with the modification shown in Figure 7.

Figure 9 is a perspective view of the plate that is adapted to be used to hold the blade on the bridge shown in Figure 8.

40 In the drawing like reference numerals indicate like parts.

In the drawing reference numeral 4 indicates the frame of the device, which frame is made of a single piece of sheet metal bent to a U-shape.

45 The sides 2 and 3 form brackets that are adapted to support the remaining parts of the device. The base 4 is adapted to rest against the side wall on which it is fastened or held. This base is

50 Figure 6, each of which openings is round at the bottom and has a short slot extending up therefrom. These openings are adapted to engage over the round heads 7 and 8 of screws, and the device is then moved down to engage the narrow

55 slots under the heads of the screws, after which

the screws can be tightened to securely hold the device in place on the side wall.

Between the sides 2 and 3 is placed a roller or sleeve 9, which is mounted to turn on a pin 10, the ends of which pin are securely held in the sides 2 and 3 in any suitable manner, permitting the sleeve or roller to turn freely thereon.

10 In each of the sides 2 and 3 blisters 11 and 12 are formed, which consists of a narrow strip of metal that is struck up and at the ends left integral with the sides 2 and 3. These blisters are formed to leave an opening 13 and 14 between the blister and the sides 2 and 3. A bridge 15 is formed having the flanges 16 and 17 on each end thereof that are adapted to engage in the openings formed by the blister, by which the bridge is held in place. This bridge has a rib 18 thereon that is adapted to engage in the slot that is provided in the Gillette razor blade 19.

A plate 20 is provided having an upturned end 21. This plate has a slot 22 cut therein that is adapted to engage on the rib 18, so that between the plate 20 and the bridge 15 the blade that is to be sharpened is securely held in place. The upturned end 21 has a lug 23 struck up therefrom that is adapted to engage in an opening 24 in the side 2 of the frame.

20 The right hand end of the plate 20 has a tongue 25 formed thereon that engages in the slot in the side 1 of the frame. This tongue is first engaged in the slot in the side 1 and then the upturned end 21 is pushed down until the lug 23 slides to position opposite the opening 24, in which it engages with a snap. This lug holds the left hand end of the plate 20 in place as shown in Figure 2, and when it is desired to remove the blade, this lug is disengaged from the slot by springing the upturned end 21 to the right in Figure 2 and then raising it.

30 In operation, the blade is placed on the bridge 15, the plate 20 is then placed thereon in the manner above described, first with the tongue 25 engaging the slot in the side 1, after which the other end of the plate is pushed down until the lug 23 engages in the slot 24 in the side 2.

40 In the forward end of the device a pin or a roller 26 is provided which engages in the curved slots 27 formed in the sides 2 and 3, in which slots the roller is free to move from one side to the other. This roller is provided with enlarged ends 28 and 29, by which the roller is held in place.

45 A strop 30 is provided which passes over the roller 9 and bears against the roller 26. This strop swings first against one side of the forward

edge of the blade and then against the other side of the blade, each end of the strop swinging first toward and beyond the plane of the blade and the plane connecting the rollers 9 and 26. This 5 strop will push the roller 26 to the one side or the other of the frame, as it is pulled, and in so doing the portion of the strop that is between the rollers 9 and 26 will be drawn forward over the edge of the blade, the strop being first held in the position 10 shown in Figure 3 and moving in the direction shown by the arrows, both ends of the strop being held down as shown in Figure 3, or being held to the left as shown in Figure 1. Both ends of the strop are then swung up from the position shown 15 in Figure 3, causing the lower end of the strop to bear against the roller 26 and move it to the other limit of its movement, in which position the strop will bear against the other side of the cutting edge of the blade. The end of the strop 20 31 is then drawn out, bearing against the one side of the cutting edge as it moves. Then the ends of the strop are swung in the other direction, and are moved in the reverse direction alternately applying the strop first to one side of the cutting 25 edge and then to the other side, the active portion of the strop always bearing against the cutting edge as the strop is drawn out. The portion of the strop that is drawn back passes clear of the cutting edge. By this alternate movement 30 of the strop, the blade is quickly and accurately sharpened.

In practice it has been found that a strop that is nine inches in length and is a little wider than the blade is sufficient for the purpose.

35 In Figure 7 I have shown a modified form of this device that is used for stropping a so-called Gem razor blade. In this figure the sides 2 and 3, the base 4, the blisters 11 and 12, and the rollers 9 and 26, and slots 27 are all the same as those 40 shown in Figures 1 and 3. Instead of the bridge 15 I use the bridge 40. The flanges 41 and 42 thereof engage in the openings 13 and 14 formed by the blisters. This bridge has a slot or opening 43 therein that is adapted to receive one side 45 of the channel 44 on which the blade 45 is mounted. A plate 46 is provided having a tongue 47 on one end that is adapted to engage a slot in the side 3, just as the tongue 25 engages in the slot in the side 3. This plate has the upturned end 48 which has a lug thereon similar to the lug 23 that engages with the slot similar to the slot 24 shown in Figure 2. This plate engages the upper side of the blade and holds it in place on the bridge, and the strop is applied thereto in 50 the same way as has been described above in connection with Figure 3.

It will be seen that the two ends of the strop are not enclosed in any way, but can be swung out sideways on the roller 9 and away from the 60 blade, thus permitting the ready removal or change of the blade. The strop is wholly guided in its movement forward and back by the rollers 9 and 26 and by the hands of the operator.

I claim:

65 1. A frame for a device for stropping razors, said frame having two parallel sides, each of said sides having an integral strap sheared therefrom and struck up inwardly to form a shoulder, and 70 a pair of slits, a bridge having a downturned flange on each end thereof adapted to engage in said pairs of slits formed by said straps, and be supported by said straps in one fixed position, by said shoulders.

75 2. In a device for stropping razor blades, the

combination of a frame having two parallel sides, each of said sides having an integral strap sheared therefrom and struck up inwardly to form a shoulder and a pair of slits, a bridge having a downturned flange on each end thereof adapted to engage in said pairs of slits formed by said straps and be supported by said straps in one fixed position by said shoulder, said bridge being adapted to support a razor blade thereon, and a plate adapted to engage with the sides and 10 clamp the razor blade on said bridge in one fixed position.

3. In a device for stropping razor blades, the combination of a frame having two parallel sides, a bridge extending along the sides from one side 15 to the other and held in one position thereon, a roller mounted between the sides having an axis fixed relative to the bridge and back of, and centrally with said bridge, a roller having a moving axis mounted in said sides in front of 20 said bridge, said roller being adapted to move back and forth from one side of the bridge to the other side.

4. In a device for stropping razor blades, the combination of a frame having two parallel sides, 25 a bridge extending along the sides from one side to the other and held in one position thereon, means for clamping a razor blade on said bridge with the edge extending forwardly therefrom, a roller mounted between the sides and back of said 30 bridge, the axis of said roller being fixed relative to said bridge, a roller having a moving axis mounted between said sides in front of said bridge, a strap passing over the roller with a fixed axis, and being adapted to be moved back 35 and forth and to pass alternately over one side of the razor blade making contact with the edge as it moves forward, the position of the strap with reference to the edge of the razor blade being fixed by the roller having the moving axis. 40

5. In a device for stropping razor blades, the combination of a frame adapted to be fastened to a support and extend outwardly therefrom, a bridge extending along the sides of said frame and fastened rigidly thereon, a roller mounted 45 in said frame back of said bridge, the axis of said roller being fixed relative to said bridge, and a roller having a moving axis mounted in front of said bridge, said bridge being adapted to hold a razor blade clamped thereon with the edge 50 projecting forwardly therefrom in one position, the roller mounted in the sides of the frame in front of said bridge being adapted to move from one side of the edge of said blade to the other side. 55

6. In a device for stropping razor blades, the combination of a frame having sides extending outwardly, a bridge extending along the sides of the frame and held fixed in one position thereon, a roller mounted between the sides, and back of, 60 and in line with said bridge, the axis of said roller being fixed relative to said bridge, a roller having a moving axis mounted in the sides of said frame in front of said bridge, said roller being adapted to move back and forth from one 65 side of the bridge to the other side.

7. A device for stropping razor blades, having a frame, a supporting plate fixed in one position thereon, said plate having front and back edges thereon, a roller mounted in said frame with its 70 axis fixed relative to said plate, a roller having a swinging axis placed forward of the front edge of said plate, said plate being adapted to hold a razor blade thereon on said plate with an edge for sharpening exposed toward the roller with the 75

swinging axis, said roller being adapted to swing from one side of the exposed edge of the blade to the other side, means for limiting the swing of said roller in each direction, a strop adapted 5 to move over the exposed edge of said blade and over said roller, said roller being adapted to position the strop correctly with reference to either or both sides of the edge being sharpened.

8. A device for stropping razor blades, having 10 a frame, a supporting plate fixed in one position thereon, said plate having front and back edges thereon, curved slots in said frame forward of the front edge of said plate, a roller mounted in said slots and adapted to be moved from one side 15 of said plate to the other side, said plate being adapted to hold a razor blade thereon with an edge for sharpening exposed toward said roller, said slots limiting the swing of said roller in each direction, a strop adapted to move over the exposed edge of said blade and over said roller, said roller at each end of its movement being adapted 20 to position the strop with reference to the side of the edge being sharpened.

9. A device for stropping razor blades, having 25 a frame, a supporting plate fixed in one position therein, said plate having front and back edges thereon, a roller placed back of one edge of the

supporting plate the axis of said roller being fixed relative to said plate, a roller with an axis swinging sideways between fixed limits placed in front of the other edge of the supporting plate, said plate being adapted to support a razor blade thereon with an edge exposed for sharpening away from the roller with the fixed axis and toward the roller with the moving axis. 5

10. A device for stropping razor blades, having 10 a frame, a supporting plate fixed in one position thereon, said plate having front and back edges thereon, a roller placed back of one edge of the supporting plate the axis of said roller being fixed relative to said plate, a roller with an axis swinging sideways between fixed limits placed in 15 front of the other edge of the supporting plate, said plate being adapted to support a razor blade thereon with an edge exposed for sharpening away from the roller with the fixed axis and toward the roller with the moving axis, a strop 20 adapted to pass over the roller with the fixed axis and make contact with the exposed edge of the blade and with the roller with the moving axis, first with one end of the strop and then with the other end of the strop. 25

CHARLES J. LAWRENCE.
